WASHING MACHINE

Robert J. Waterworth and Richard J. O'Connor,
Sidney, Ohio, assignors to Prima Manufacturing Company, Inc., Sidney, Ohio, a corporation of Ohio

Application April 28, 1930, Serial No. 447,942

7 Claims. (Cl. 68—15)

This invention relates to improvements in washing machines, and has for its object the provision of means for mounting porcelainized or vitreous enameled tubs upon the base or support in such a manner that expansion and contraction may occur without injury to the enameled surfaces of the tub.

It is particularly the object of this invention to provide a base or support for a tub upon which the tub is mounted upon resilient discs or gaskets in such a manner that any movement of the tub in relation to the chassis will not injure the surfaces of the tub.

It is also an object of this invention to provide in connection with a porcelainized tub a faucet thereon so connected to the tub that it can be easily removed, and when in place is guided by a side flange of the chassis.

It is also an object of this invention to provide in connection with the base or support having a standard, a means for supporting the tub from a standard in such a manner that a limited amount of movement is permitted to the tub without the outside surface of the tub coming in contact with the parts of the standard that support it. For this purpose there is provided in connection with the supporting means attached to the standard a plurality of rubber discs engaging the tub in such a manner as to hold it but at the same time permit a limited amount of movement of the tub.

These and other objects will appear in the following description taken in connection with the drawings.

35 Referring to the drawings:

Figure 1 is a view showing a vertical section of the tub and the base or support, together with the standard and gear case.

Figure 2 is an enlarged view of the arm 9 extending from the standard and shows the means by which the side of the tub is attached to the standard.

Figure 3 is a top plan view of the base or support.

45 Figure 4 is a section on the line 4—4 of Figure 1.

Figure 5 is a section on the line 5—5 of Figure 1.

Figure 6 is a section on the line 6—6 of Figure 1.

This invention relates to washing machines, and particularly the manner of mounting the tub upon a base or support 1. This base or support is circular in shape, and has extending downwardly from the periphery thereof a flange 2.

The central part of the base or support has an opening 3 through which the operating shaft extends from the gear within the gear housing.

Located around the opening 3 and beneath the base or support is a bracket ring 4, which has 60 extending downwardly therefrom a plurality of arms 4' ending in a plate or disc 5. To this plate or disc is attached a gear case 6, which is also further supported from the chassis by means of a bolt connection 7. Extending from one side 65 of the gear housing and external to the base or support and the tub is a standard 8, which has extending from one side thereof an arm 9 the purpose of which will be described hereinafter.

In the base or support there is a plurality of 70 depressions 10, which have extending through the bottoms thereof holes through which bolts 11 extend for the purpose of fastening legs to the base or support. On top of the heads of the bolts in the depressions are resilient discs 12 of 75 substantially the same size the depressions are. These resilient discs are for the purpose of supporting the bottom of the tub upon the base or support. Supported upon the base or support is a tub having sides 13 and a bottom 14. The 80 bottom of the tub rests upon the resilient discs 12 and has in the center thereof an opening 15 in line with and the same size as the opening in the base or support.

Between the base or support and the bottom 85 of the tub and surrounding the openings in the base or support and the tub is a rubber washer 16. Extending upwardly from the center of the tub is a dolly standard 17, which has at its lower end a base flange 18 resting upon a rubber washer 90 or gasket 19 between the base of the dolly standard and the bottom of the tub.

As shown in Figures 1 and 5 these parts are attached to each other by means of screws 20 which pass through holes 21 in the bottom of the 95 tub and holes 22 in the base or support. These holes are somewhat larger than the screws 20 to permit movements of the bottom of the tub and the base or support in relation to these screws. These parts are firmly held together by means 100 of the screws 20, which may be easily placed in position and may be easily removed therefrom. For the purpose of holding the parts assembled, as shown in these figures, the threaded ends of the screws are threaded into the bracket ring 4 105 beneath the base or support.

As shown in Figure 3 there is a plurality of resilient discs 12 associated with the bolts for attaching the legs to the chassis. Upon these resilient discs the tub rests and is supported, while 110

the central part of the bottom of the tub is supported on the annular gasket or washer 16.

It is obvious that a tub supported in the manner hereinbefore shown and described may have a certain amount of movement without the surfaces of the tub becoming injured. In the case of enameled tubs it is very necessary that the surface of the tub be kept free from scars and chipped places. It is therefore the object of this invention to provide means for supporting a tub in such a manner that all supporting contacting surfaces are lined with resilient discs or resilient gaskets so that no contact of enameled surfaces with metal is permitted, the tub being supported at all points from direct contact with any of the metal parts of the supports.

To one side of the tub and in the bottom thereof there is a conical depression terminating at the bottom into an orifice 23, circular in shape. 20 There is also in the part of the base or support adjacent the hole 23 of the tub a hole 25 in line with but considerably larger than the orifice in the tub. This hole in the base or support is for the purpose of accommodating a faucet 26, which 25 is attached to the downwardly turned edges of the orifice 23 and extends through the hole 25 in the base or support.

The upper end of the faucet is flared at 27 and fits on the outside of the downwardly turned 30 edges of the orifice 23 as hereinbefore described. On the inside of the faucet adjacent the flared mouth is a threaded throat 28, into which a flared nipple 29 is threaded. This flared nipple threaded externally on its cylindrical portion 30 screws 35 into the internally threaded throat part of the faucet. The upper end of the spout 29 is flared at 31 and conforms to the general shape of the flared mouth of the faucet but providing a space therebetween for the flared edges of the orifice 40 23 hereinbefore described.

Between the part 31 and the downwardly turned edges 24 is a resilient gasket 32, while between the flared mouth 27 and the downwardly turned edges 24 is a gasket 33. These parts are 45 shown in Figure 4. The parts 31 and 27 are clamped against the gaskets by the rotation of the spout 29, bringing the parts close in relation to each other so that the gaskets are compressed between the parts 27 and 31 respectively, and the 50 downwardly turned edges 24 so that when the nipple is screwed down the faucet is held firmly to the bottom of the tub so that no solution can leak through the connection between the two.

In the lower and outer end of the faucet is a 55 valve 34 operated by means of a valve stem 35 threaded into an opening in the wall of the faucet. This stem and valve are operated by means of a wing structure on the outer end of the stem. This wing structure extends through 60 a slot 36 in the peripheral flange 2 of the base or support. This slot permits a certain amount of movement of the valve stem without being interfered with by the walls of the flange. Beneath the valve stem there extends a locating 65 stud 37. This stud projects from the faucet through opening 38 in the flange of the base or support. This opening is below the opening 36 and permits a free movement of the faucet without being interfered with by the flange of the 70 base or support. The large hole 25 in the base or support permits a movement of the faucet without engaging the base or support either by any movement of the faucet and the tub.

For the purpose of supporting the side of the 75 tub there is provided in connection with the arm

9 an opening 39 in the wall of the tub, a resilient gasket or washer ring 40 between the arm and the tub, a similar resilient washer 41 on the inside of the tub, a cap member 42 fitting over the resilient washer 41, and a bolt 43 passing through the cap, both resilient washers, through the opening 39 and through a hole in a projection on the arm 9. By this means the side of the tub is held by the standard 8 in such a manner that a limited amount of movement can occur to the tub without the surface of the tub coming into contact with any object other than that of the resilient washers or gaskets. In order to provide for this movement and this protection, hole 39 diametrically larger than the bolt is provided for the bolt 43.

It is obvious from the foregoing description that any part of the tub cannot contract with a metal surface or metal support, all contracting 80 points of the surfaces of the tub being supported by a resilient disc or gasket. It is also obvious that any slight movement of the tub permitted by these resilient gaskets can be effected without any part of the tub becoming marred or worn by contact with a hard metal surface. It is also 85 obvious that the faucet, supported from the bottom of the tub, is attached in such a manner that there is a watertight connection between the bottom of the tub and the faucet, and that the faucet is also located by openings in the periphery of the base or support in such a manner that it can have a limited amount of movement without coming into contact therewith; at least without coming into contact with the base or support in such a manner as to cause marring or 90 breaking of the apparatus or machine. This support for the tub is particularly advantageous to tubs composed of metal porcelained or vitreous enameled.

We desire to comprehend within our invention 105 such modifications as may be clearly embraced within our claims and the scope of our invention.

Having thus fully described our invention, what we claim is new and desire to secure by Letters Patent, is:

1. In a washing machine, a support having a plurality of depressions with holes therein, a leg-attaching bolt in each hole with its head in the depression, a resilient disc in each depression on the head, and a tub mounted above said support 125 on said resilient discs whereby the tub is supported free from contact with the support.

2. In a washing machine, a support having an opening therein, a tub spaced from the support having an opening in line with the opening in the support, a resilient gasket between and engaging the tub and the support and around said openings, a resilient gasket on said tub around the opening therein, a dolly standard having a base resting upon and above said last resilient gasket, and means for holding the dolly standard, the gaskets and the tub on the support, all constructed so that the tub and dolly standard are so mounted on the support that the tub is free from direct contact with either the support or the standard.

3. In a washing machine, a support having an opening therein, a tub having an opening in the bottom thereof in line with the opening in the support, a plurality of resilient discs each engaging the support and the tub bottom, and a resilient gasket ring between the bottom of the tub and the support and around said openings whereby the tub is mounted on the support without direct contact therewith.

4. In a washing machine, a support having an opening therein, a supporting bracket having a ring fitting around said opening beneath and against the support, a tub having an opening in the bottom thereof in line with the first named opening, a dolly standard having a base flange around the opening in the tub bottom, a gasket between the bottom of the tub and said support, a second gasket between the tub and the dolly standard, and means for clamping said support ring tub bottom, base flange, and gaskets together whereby they are held together with the tub free from contact with the support and the dolly standard. 80
- 15 5. In a washing machine, a support having a hole therein, a tub resiliently affixed to said support, a faucet attached at one end to said tub extending through said hole and means on said support spaced from said first hole for slidingly receiving the other end of said faucet whereby the faucet has a limited amount of free movement with relation to the support. 90
- 20 6. In a washing machine, a support having a

hole therein and a peripheral downturned flange, a plurality of cushioned means on said support, a tub mounted on said cushioned means, said tub having a hole with turned-down edges over the first hole, a faucet having a cushion connection with said turned-down edges and projecting through said first-named hole, and means on said flange and faucet to guide the latter in its movement due to the cushioned supports of the tub and the cushioned connection of the faucet. 95
